US0D1099136S

(12) **United States Design Patent** (10) Patent No.: **US D1,099,136 S**
(45) Date of Patent: ** Oct. 21, 2025

(54) **DISPLAY SCREEN OR PORTION THEREOF WITH GRAPHICAL USER INTERFACE**

(71) Applicant: **Lingo Sensing Technology Unlimited Company**, Dublin (IE)

(72) Inventors: **Rachel A. Florenza**, Santa Clara, CA (US); **Olga Kraineva**, San Francisco, CA (US); **Benjamin G. Fohner**, San Francisco, CA (US)

(73) Assignee: **Lingo Sensing Technology Unlimited Company**, Dublin (IE)

(**) Term: **15 Years**

(21) Appl. No.: **29/932,033**

(22) Filed: **Mar. 11, 2024**

(51) LOC (15) Cl. **14-04**

(52) U.S. Cl.

CLAIM

The ornamental design for a display screen or portion thereof with graphical user interface, as shown and described.

DESCRIPTION

The patent file contains at least one drawing executed in color. Copies of this patent with color drawings will be provided by the Office upon request and payment of the necessary fee.

The FIGURE is a front view of a display screen or portion thereof with graphical user interface showing our new design.

The outer perimeter illustrated by dashed broken lines in the FIGURE illustrates a display screen or portion thereof and forms no part of the claimed design.
